UNITED STATES PATENT OFFICE.

ALBERT G. McGARVEY, OF WILKINSBURG, PENNSYLVANIA, ASSIGNOR TO WESTINGHOUSE ELECTRIC AND MANUFACTURING COMPANY, A CORPORATION OF PENNSYLVANIA.

CLINKER GRINDER.

Application filed September 16, 1921. Serial No. 501,063.

To all whom it may concern:

Be it known that I, ALBERT G. McGARVEY,
a citizen of the United States, and a resident
of Wilkinsburg, in the county of Allegheny
5 and State of Pennsylvania, have invented
a new and useful Improvement in Clinker
Grinders, of which the following is a speci-
fication.

10 This invention relates to clinker grinders for mechanically operated furnaces and has for an object to provide in an apparatus of the character designated a device associated with an intermediate bearing of a grinder roll, which shall serve to guide and properly 15 to feed the refuse in the lower portion of the clinker pit onto the clinker roll, and which shall at the same time offer a minimum supporting surface for the refuse and prevent the lodgment of refuse upon the 20 bearing and the bearing support. It is a further object of my invention to provide, in addition, a means for cooling such device and its associated bearing, and also to provide in connection therewith means for cooling 25 all metallic parts in the lower portion of the clinker pit and for chilling the refuse suddenly so as to render the clinker content thereof friable.

In the accompanying drawings, Fig. 1 is a vertical longitudinal view, partially in section and partially in elevation, taken through the clinker pit of a multiple retort stoker, illustrating the construction and the disposition of my improved fluid cooled bearing cap to intermediate bearings of the grinder rolls;

Fig. 2 is a fragmentary plan view of the clinker pit disclosed in Fig. 1, illustrating the relation of the clinker pit and bearing cap to the stoker retorts and twyers; and

45 bearing cap taken on line III—III and line IV—IV, respectively, of Fig. 1.

50 Clinker grinders are commonly employed only in boiler installations of considerable size, and, consequently, the clinker pit near the bottom of which the grinder rolls are located is comparatively long. It becomes necessary, therefore, to provide the shafts of the grinder rolls with one or more intermediate bearings. As heretofore constructed, these intermediate bearings, being in contact with the hot refuse which tends to

adhere thereto, have served as shelves for the lodgment and accumulation of refuse, which, at times, bridges the pit from side to side, and materially interferes with the efficient operation of the grinder rolls. 55

These difficulties I overcome by the provision of a wedge-shaped, fluid-cooled bearing cap which overlies each intermediate bearing and bearing support, and which prevents refuse from lodging upon and adhering to the grinder bearings and supports therefor, thus contributing to a more uniform disposal of the refuse by the grinder rolls. I furthermore provide a series of apertures on each side of, and near the upper edge of the wedge-shaped bearing cap for directing streams of cooling fluid from the caps into the clinker pit. This quenches any fuel still in process of combustion and suddenly chills the refuse so as to render the clinker therein friable prior to its passage through the grinder rolls.

Referring to the drawing for a detailed understanding of an apparatus embodying my invention, I have illustrated a clinker pit employed in conjunction with a multiple retort underfeed stoker and have generally indicated the stoker by the numeral 10, and the clinker pit by the numeral 11. The stoker 10 comprises the usual alternate arrangement of retorts 12, twyers 13, and extension plates 14, (see Fig. 2) over which the ash, the clinker and any unburned fuel passes into the clinker pit. The clinker pit illustrated has its front and rear walls each formed by a grate box 15, and an apron 17. It is to be understood, however, that the clinker pit may be constructed in any suitable manner, the invention herein disclosed being in no way limited in its employment to any specific form of clinker pit.

Extending longitudinally of and forming the bottom of the clinker pit are grinder rolls 20, comprising rotatable shafts 21 and grinding members mounted thereon. The ends of these shafts may be journaled in the side walls of the furnace structure in any suitable manner. Intermediate bearings for the shafts are provided, each bearing comprising a lower bearing block 23, which is supported from beams 24, secured to and forming a part of the furnace frame 25, and an upper bearing block 26 secured to the

lower bearing block 23, as by bolts 27. The grinder rolls may be each provided with a plurality of teeth or cutters 28, in a manner common in grinder roll construction.

As illustrated in the drawings, a fluid-cooled bearing cap, generally designated by numeral 30, is supported upon the upper block 26. The cap is wedge-shaped in section, the edge of the wedge being upwardly presented, and is provided with a base portion 31 of dimensions coextensive with the upper surface of block 26, to which it is secured by bolts 32. It is within the purview of the present invention, however, to make the upper bearing block 26 and the cap 30 of a single casting, a construction which has been found to be preferable in some installations. A main chambered portion 33 of the bearing cap is connected to the base portion by a central chambered portion 34, and by webs 35 located on each side thereof. The ends of the chamber portion 33 of the cap are inclined so as to lie adjacent to the inclined aprons 17 of the clinker pit. Apertures 37 are provided in each side of the main chambered portion 33, preferably near the upper edge thereof, through which streams of the cooling fluid are delivered into the clinker pit. The cooling fluid, as for example, water, is supplied to the cap 30, through a conduit 38, which preferably delivers the cooling fluid into the central portion 34 of the cap.

The manner in which the fluid-cooled bearing cap facilitates the operation of the clinker-grinder is apparent from the above description. In brief, the hot refuse, which is continuously passing downwardly through the clinker-pit, contacts on approaching the grinder rolls first with the fluid cooled bearing caps. Due to the low temperature of the caps, there is little or no tendency for the hot refuse to adhere to the cool bearing cap and, consequently, the refuse is guided downwardly onto the grinder rolls, where it is crushed and positively discharged. This enables the grinder rolls to operate at full capacity since any lodgment of the refuse upon the bearing or bearing support and any consequent bridging of the refuse therefrom is eliminated. Furthermore, when the refuse has reached the lower portions of the ash pit, it has passed the zone in which combustion of any unburned fuel can take place. The spraying of the refuse at this point cools the ash and renders friable any clinker portions thereof. The cool refuse is more readily crushed by the grinder rolls, and passes through the rolls without adhering thereto and without clogging or minimizing the effective discharge area of the clinker pit.

My invention has been illustrated and described in connection with a two-roll clinker grinder. It is evident, however, that the fluid cooled cap disclosed herein is applica-

ble to the intermediate bearings of a grinder roll in clinker pits in which one roll only is employed, a type commonly used in ash disposal mechanisms.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:—

1. In combination in a clinker pit, a grinder roll in the lower portion thereof, a bearing for said roll intermediate the ends of said pit, and means including a guide member overlying the portion of said roll engaging with said bearing for rendering the clinker portion of the refuse friable.

2. In combination in a clinker pit, a grinder roll in the lower portion thereof, a bearing for said roll intermediate the ends of said pit, and means including a guide member overlying said bearing for cooling the metallic parts in the lower portion of the clinker pit and rendering the clinker portion of the refuse friable.

3. The combination with a clinker pit having a grinder roll in the lower portion thereof and a bearing for said roll intermediate the ends of said pit, of a bearing cap overlying said intermediate bearing, and means for supplying cooling liquid to said cap, said cap being formed to discharge said liquid therefrom and to the interior of said pit.

4. The combination with a clinker pit having a grinder roll in the lower portion thereof and a bearing for said roll intermediate the ends of said pit, of a hollow bearing cap overlying said intermediate bearing, and means for circulating a cooling fluid through the hollow in said cap, said cap being formed to discharge said liquid therefrom and to the interior of said pit.

5. The combination with a clinker pit having a grinder roll in the lower portion thereof and a bearing for said roll intermediate the ends of said pit, of a hollow-chambered bearing cap overlying said intermediate bearing, means for admitting a cooling fluid under pressure into said cap, and means for delivering the fluid in small streams from the cap into the clinker pit.

6. The combination with a clinker pit having a grinder roll in the lower portion thereof and a bearing for said roll intermediate the ends of said pit, of a hollow wedge-shaped bearing cap overlying said intermediate bearing, the edge of the wedge-shaped cap being at the top of the cap and the base of the wedge-shaped cap overlying said intermediate bearing, and means for supply-

ing cooling liquid to said cap, said cap being formed to discharge said liquid therefrom and to the interior of said pit.

7. The combination with a clinker pit having a grinder roll in the lower portion thereof, and a bearing for said roll intermediate the ends of said pit, of a hollow wedge-shaped bearing cap overlying said intermediate bearing, the edge of the wedge-shaped cap being at the top of the cap and the base of the wedge-shaped cap overlying said intermediate bearing, and means for admitting a cooling fluid under pressure into said cap, said cap having apertures in the sides thereof for delivering the cooling fluid in small streams into the clinker pit.

8. In a furnace, the combination with a clinker pit having a plurality of grinder rolls extending longitudinally through the lower portion of the pit, and transversely aligned bearings for each of said rolls intermediate the ends of the pit, of a bearing cap overlying the aligned bearings, and means for circulating a cooling liquid through said cap and discharging said liquid into the interior of said pit.

9. In a furnace, the combination with a clinker pit having a plurality of grinder rolls extending longitudinally through the lower portion of the pit, and transversely aligned bearings for each of said rolls intermediate the ends of the pit, of a hollow-chambered bearing cap overlying the aligned bearings, and means for circulating

a cooling liquid through the chamber in said cap and discharging said fluid into the interior of said pit.

10. In a furnace, the combination with a clinker pit having a plurality of grinder rolls extending longitudinally through the lower portion of the pit and transversely aligned bearings for each of said rolls intermediate the ends of the pit, of a hollow-chambered bearing cap overlying the aligned bearings, means for admitting a cooling fluid under pressure into said cap, and means for delivering the fluid in small streams from the cap into the clinker pit.

11. In a furnace, the combination with a clinker pit having a plurality of grinder rolls extending longitudinally through the lower portion of the pit, and transversely aligned bearings for said rolls intermediate the ends of the pit, of a hollow wedge-shaped bearing cap overlying said intermediate bearings, the edge of the wedge-shaped cap being at the top of the cap and the base of the wedge-shaped cap resting upon said intermediate bearings, and means for admitting a cooling fluid under pressure into said cap, and said cap having apertures in the sides thereof for delivering the cooling fluid in small streams into the clinker pit.

In testimony whereof, I have hereunto subscribed my name this 6th day of September, 1921.

ALBERT G. McGARVEY.
